UNITED STATES PATENT OFFICE.

LUDWIG KOLOS, OF DEBRECEN, HUNGARY.

GYMNAStic APPLIANCE.

Application filed April 6, 1927, Serial No. 181,569, and in Hungary April 26, 1926.

This invention relates to gymnastic appliances, more particularly appliances used for Swedish exercises, and has for its object to provide an appliance which combines or 5 replaces the "wall bars", the bench, the table and the horizontal bar. An appliance according to the invention takes up relatively little space, is easily portable and can therefore be used both in the open air and in 10 enclosed places.

A gymnastic appliance in accordance with the invention consists substantially of an H-shaped frame composed of two longitudinal beams and a shorter intermediate 15 part connecting the longitudinal beams, the whole resting on feet and having at one end a transverse rod fixed above the longitudinal beams at a distance from the intermediate part, which will enable the head or other 20 parts of the body to be pushed through. This transverse rod extends laterally beyond the longitudinal beams and acts as a grip or horizontal bar. In a modification of the 25 gymnastic appliance having no frame the horizontal bar is fixed at two intermediate points at a level slightly exceeding that of the recumbent human body to two heavy blocks or to two pegs or bars extending upwards from the ground or floor, the frame 30 being replaced by a thick raised mat.

With a gymnastic appliance in accordance with the present invention all manner of 35 gymnastic exercises, may be performed, the appliance being capable of being used for supporting the body while leaving the head and limbs free to move.

In the accompanying drawing various 40 constructional forms of gymnastic appliances according to the present invention is shown by way of example.

Figure 1 is a perspective view of the first 45 constructional form,

Figure 2 a perspective of the second constructional form,

Figure 3 a perspective view of a part of 50 a third constructional form, and

Figure 4 a plan view of two gymnastic appliances according to the invention connected together.

55 The gymnastic appliance shown in Figure 1 is composed of the two longitudinal beams 1^a, 1^a resting on feet 2, the transverse beams 1^b, 1^b connecting the said longitudinal beams and the two beams 1^c, 1^c which connect the two transverse beams 1^b, 1^b are parallel to 60 the longitudinal beams 1^a and are substan-

tially shorter than the latter. On the longitudinal beams 1^a, 1^a near one end of the same a wooden or metal horizontal bar or gripping bar 3 is fixed by means of supports 3^a, the bar extending on either side beyond the longitudinal beams 1^a, 1^a. The bar 3 is at such a distance from the adjacent transverse beam 1^b that, when the appliance is in use, the head of the person 65 using the appliance can be lowered into the space thus formed or that other parts of the body can be passed through for gripping the rod 3 from below. The space formed at the other end of the appliance between the ends of the longitudinal bars and the transverse bars is of importance, when the appliance is in use, for lowering any other parts of the body. The holes 1^d formed in the longitudinal beams 1^a permit 70 of the horizontal bar 3 being adjusted by means of thumb screws or the like.

A particular advantage of the new gymnastic appliance consists in this, that the spine resting on the appliance is bent slightly 75 backwards and that the chest will be automatically thrown out, while the body is at rest. The middle part of the horizontal bar 3 completely replaces the ordinary horizontal bar for balancing exercises and is 80 perfectly rigid, as it lies between the points of support formed by the feet 2 on the longitudinal beams 1^a.

The gymnastic appliance can be used both 85 in the horizontal and in an inclined position, being for instance supported by the feet 2 on a window sill or on the edge of 90 any piece of furniture.

In the longitudinal slot between the beams 1^e, 1^e a slidible pad may be provided, which 95 may be used with advantage more particularly in the case of children who hold themselves badly or are suffering from curvature of the spine.

In a modified form of the appliance the 100 middle part of the H-shaped frame may be made in the form of a continuous plate.

In the constructional form shown in Figure 2 the horizontal bar 3 is fixed at a level slightly above that of the recumbent human 105 body to heavy blocks 4, the wooden frame being replaced by a thick, slightly raised mat laid on the ground. The blocks 4 may be replaced by pegs or bars fixed in the ground. This constructional form is particularly suitable for use at seaside bathing 110 places and sports grounds.

2
 In place of all the feet 2 or in place of the feet at one end of the appliance only hooks 2^a may be provided, as shown in Figure 3, by means of which the appliance can 5 be suspended in an inclined or vertical position to a bar. The part of the hooks 2^a, by which they are fixed to the longitudinal beams, are preferably so shaped as to form eyes 2^b, which can then be used as shown in 10 Figure 4 to unite several places in the form of a ladder, pins 5 being inserted through the eyes 2^b of the adjacent ends of two appliances. The connection between two appliances may of course be effected in any other 15 suitable manner.

What I claim is:

1. A gymnastic appliance comprising a substantially H-shaped frame constituted by two longitudinal beams, an intermediate 20 part between the two beams for connecting them together, the said part being shorter than the beams, supports for the frame and a transverse bar fixed to the longitudinal beams near one end of the same at a short 25 distance from them and at a sufficient distance from the said intermediate part, to allow the head and other parts of the body to pass through and having its ends extending laterally beyond the longitudinal beams, 30 as and for the purpose set forth.
2. A gymnastic appliance as claimed in claim 1, and having some of the supports in the form of hooks, as and for the purpose set forth.
3. A gymnastic appliance comprising a substantially H-shaped frame constituted

by two longitudinal beams, an intermediate part between the two beams for connecting them together, the said part being shorter than the beams, a longitudinal slot in the 40 said intermediate part of the frame, a raised pad capable of being slid longitudinally of the said slot, means for fixing the pad in any position, supports for the frame and a transverse bar fixed to the longitudinal beams 45 near one end of the same at a short distance from them and at a sufficient distance from the said intermediate part, to allow the head and other parts of the body to pass through and having its ends extending laterally beyond the longitudinal beams, as and for the 50 purpose set forth.

4. A gymnastic appliance comprising a substantially H-shaped frame constituted by two longitudinal beams, an intermediate 55 part between the two beams for connecting them together, the said part being shorter than the beams, supports for the frame, a transverse bar fixed to the longitudinal beams near one end of the same at a short 60 distance from them and at a sufficient distance from the said intermediate part, to allow the head and other parts of the body to pass through and having its ends extending laterally beyond the longitudinal beams, 65 and means for adjusting the transverse bar longitudinally of the said beams, as and for the purpose set forth.

In testimony whereof I have signed my name to this specification.

LUDWIG KOLOS.
